UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ELECTROPNEUMATIC BRAKE.

1,283,981.

Specification of Letters Patent.

Patented Nov. 5, 1918.

Application filed September 14, 1917. Serial No. 191,388.

To all whom it may concern:

Be it known that I, WALTER V. TURNER, a citizen of the United States, residing at Wilkinsburg, in the county of Allegheny and 5 State of Pennsylvania, have invented new and useful Improvements in Electropneumatic Brakes, of which the following is a specification.

This invention relates to electro-pneumatic brakes, and has for its principal object to improve on the construction covered by my prior pending application, Serial No. 158,185, filed March 29, 1917.

In the above application, an electric magneto generator operated by fluid under pressure from the brake system is employed for generating current to effect the simultaneous transmission of the braking action throughout the train.

20 The magneto generator comprises permanent magnets and an armature having a coil in which electric current is generated by moving the permanent magnets away from the coil.

25 With the above construction, the magnetic lines of force of the magnets only cut the coil once when the device is actuated, so that large magnets are required in order to generate sufficient current for the required purpose.

30 The to and fro movement of the permanent magnets also tends to jar same, and this has a tendency to weaken the magnetic force.

35 Another difficulty is that dirt particles are liable to lodge between the contacting surfaces of the magnets and the armature, so that an air gap is introduced which reduces the number of lines of force cut when the 40 magnets are pulled away from the armature and consequently the amount of current generated is reduced.

According to my present invention, the above difficulties are overcome by employing 45 a magneto having a rotating armature.

In the accompanying drawing; Figure 1 is a sectional view of an electro-pneumatic brake device embodying my invention, and Fig. 2 an elevational view of the magneto 50 portion thereof.

As shown in the drawing, the construction may comprise a triple valve device 1

having a bracket 2, attached to the rear head and to which is secured an electro-pneumatic portion 3.

55

The triple valve device 1 may comprise the usual casing having a piston chamber 4 connected to brake pipe 5 and containing piston 6 and valve chamber 7 connected by passage 8 and pipe 9 to auxiliary reservoir 10 60 and containing a main slide valve 11 and a graduating slide valve 12.

The electro-pneumatic portion 3 may comprise a casing containing a relay valve 13, a pilot valve 14 controlled by a magnet 15, 65 and a magneto generator comprising a permanent magnet 16 having between its poles a rotating armature 17 wound with the usual coil.

70 For rotating the armature 17, the armature shaft is provided with a pinion 18, the teeth of which are adapted to mesh with the teeth of a rack 19 and carried by said rack is a piston 20 adapted to be actuated by fluid under pressure.

75

The brake system is charged in the usual manner from the brake pipe 5, and in addition fluid is supplied from the auxiliary reservoir 10 through passage 21 to the outer seated area of the relay valve 13 and thence 80 equalizes through a restricted port 22 to the opposite side of said valve, and the pilot valve 14 being normally closed, fluid pressures equalize on opposite sides of the relay valve 13, so that spring 23 can hold the relay 85 valve seated, the inner seated area of the relay valve being subject to the atmospheric pressure at this time, through passage 24, cavity 25 in slide valve 11 and exhaust port 26.

90

In a service application of the brakes, the operation is the same as usual, the triple valve device operating upon a gradual reduction in brake pipe pressure to supply fluid from the auxiliary reservoir 10 to the 95 brake cylinder 27.

Upon making a sudden reduction in brake pipe pressure, however, to effect an emergency application of the brakes, the triple valve piston 6 moves to emergency application position and uncovers passage 24. Fluid is then supplied from the auxiliary reservoir to passage 24 and flows to passage 28 leading to piston 20, so that said piston 100

is operated and the rack 19 is shifted to cause the rotation of pinion 18 and the armature 17 of the magneto generator.

Current is consequently generated in the 5 armature coil and is supplied through the circuit wires 29 and 30 to the magnets 15 in the train so far as the voltage of the magneto will permit. The energization of the magnets 15 operate on each car to open the 10 pilot valve 14, so that fluid under pressure is vented from the spring side of the relay valve 13 through passage 31 to exhaust port 32.

The relay valve 13 is then shifted to its 15 open position in which fluid is supplied from the auxiliary reservoir 10 through passage 21 to passage 28 and thence past check valve 33 to a passage 34 leading to the piston chamber of the usual quick action piston 20 35, thus causing the quick action piston to actuate the quick action valve 36 so as to vent fluid from the brake pipe 5 and thus produce quick serial action throughout the train.

25 Fluid supplied to passage 28 also flows to the piston 20 and operates same to cause the rotation of the magneto armature, as before described. Current generated by the magneto on this car is then supplied to other 30 adjacent cars so far as the voltage generated is able to carry it.

In order to obtain increased rotative movement of the magneto armature, a fly-wheel 37 is mounted on the armature shaft 35 and when the piston 20 moves out, the teeth of rack 19 finally move out of engagement with the teeth of pinion 18 and this permits the momentum of the fly wheel to rotate the magneto armature to some extent after the 40 rack has ceased its movement.

In order to release the brakes, the brake 45 pipe pressure is increased to effect the movement of the triple valve piston 6 to release position in the usual way. In release position of the main slide valve 11, cavity 25 connects passage 24 with exhaust port 26, so that fluid is vented from the face of the relay valve 13, causing same to be shifted to its seat by spring 23.

Having now described my invention, what 50 I claim as new and desire to secure by Letters Patent, is:—

1. In an electropneumatic brake, the combination with a device controlled by fluid under pressure for effecting an application 55 of the brakes, of an electric generator having a rotatable armature, means operated by fluid under pressure for effecting the rotation of said armature, and means controlled by current from said generator for 60 varying the fluid pressure on said brake controlling device.

2. In an electropneumatic brake, the combination with a device controlled by fluid under pressure for effecting an application 65 of the brakes, of an electric generator having a rotatable armature, a rack and pinion for rotating said armature, a piston operated by fluid under pressure for actuating 70 said rack and pinion, and means controlled by current from said generator for controlling the fluid pressure on said brake controlling device.

3. In an electro-pneumatic brake, the combination with a brake pipe and a valve 75 device operated upon a reduction in brake pipe pressure for effecting an application of the brakes, of an electric generator having a rotatable armature, means operated by fluid under pressure supplied by said valve 80 device upon applying the brakes for rotating said armature, and means controlled by current from said generator for effecting an application of the brakes.

4. In an electro-pneumatic brake, the 85 combination with a fluid pressure brake, of an electric generator having a rotatable armature, means operated by fluid from the brake system for rotating said armature, mechanism controlled by current from said 90 generator for effecting an application of the brakes, and a fly-wheel rotating with said armature for rotating said armature after said means ceases to act.

In testimony whereof I have hereunto set 95 my hand.

WALTER V. TURNER.
